UNITED STATES PATENT OFFICE.

GEORGE H. WARREN, OF TAMA CITY, IOWA.

SULKY-PLOW.

SPECIFICATION forming part of Letters Patent No. 225,668, dated March 16, 1880.

Application filed December 18, 1879.

To all whom it may concern:

Be it known that I, GEORGE H. WARREN, of Tama City, in the county of Tama, and in the State of Iowa, have invented certain new and useful Improvements in Sulky-Plows; and I do hereby declare that the following is a full, clear, and exact description thereof, reference being had to the accompanying drawings, and to the letters of reference marked thereon, making a part of this specification.

The nature of my invention consists in the construction and arrangement of a sulky-plow, as will be hereinafter more fully set forth.

In order to enable others skilled in the art to which my invention appertains to make and use the same, I will now proceed to describe its construction and operation, referring to the annexed drawings, in which—

Figure 1 is a rear elevation of my sulky-plow. Fig. 2 is a side view of the same. Fig. 3 is a perspective view of one of the wheel-slides.

A represents the axle, to which the tongue B is firmly secured. At each end of the axle 25 A is a vertical downwardly-projecting standard, C, to receive a slide, D, which has side grooves, a a, to grasp flanges on the standard, and also a central upwardly-projecting rack-bar, b, which lies in a groove in the standard. 30 The slide D is further provided with a spindle, e, on which the wheel E is placed.

F is a bail, having its side arms pivoted in the lower ends of the standards C, and extending rearward, for supporting one or more plows. 35 G is a rigid bail, secured to the standards and to the tongue. One of the side arms of the bail F has a projection, H, extending forward at an angle, and its forward end then connected by braces I I with the bail. Between the forward ends of these braces is mounted a roller, d, on which operates a cam-lever, J, pivoted between ears on the front of the axle, for raising and lowering the bail.

One or more rollers or slides may be used 45 in connection with the cam-lever and the parts so arranged that the relative position or situation of power, resistance, or fulcrum is changed from a given point or points or radius in use.

50 The braces I answer the double purpose of holding the roller and strengthening the bail.

The two rack-bars b b of the wheel-slides D D are operated by segmental racks K K, pivoted in slots or mortises in the ends of the axle, and one of said racks is provided with a lever, L. 55

The two racks are connected by two rods, i i, clamped together by a clamp, h, so as to be adjustable, if desired, though one continuous rod may answer the purpose.

When the wheels are adjusted the rod or 60 rods i are held in a fixed position by a clamp, M, or by a dog on the lever or other fastening device.

It will be noticed that with this device there is a double or simultaneous movement of the 65 wheels—one up and the other down—whereby the sulky can be put in a level position, when one wheel is in a furrow or the sulky is on inclined ground, by the use of one lever or similar device used by hand, foot, or other 70 power.

N is the plow-beam, having its forward end connected, by a clamp, O, with a rod, P, and this rod adjustably connected to a foot-lever, R, pivoted to the side of the tongue, by means 75 of which the forward end of the plow may be raised or lowered at pleasure. When the forward end of the plow is raised while moving, the plow will rise out of the ground, as at the end of a furrow or over an obstruction, without being lifted, and when the forward end of the plow is lowered the plow will run deeper 80 into the ground without being pushed in or forced in by weights.

The plow-beam N passes over the bail F, and 85 is connected thereto by clamps S S, connected by screws or bolts m m. Each side of this clamp is made in two parts, fastened by bolts or screws around the bail, so that they may be put on or removed without interfering with the 90 fastenings of the bail.

The clamp O, which connects the rod P to the forward end of the plow-beam, has a pin, n, on which said rod is placed, whereby there is a free motion allowed the same backward and 95 forward.

Having thus fully described my invention, what I claim as new, and desire to secure by Letters Patent, is—

1. In a sulky-plow, the combination of the 100 pivoted bail F with arm H, the braces I I, roller d, and cam-lever J, all constructed and

arranged to operate substantially as and for the purposes herein set forth.

2. The combination, with the wheel-slides D D, having rack-bars *b b*, of the segmental racks K K, connecting rod or rods *i*, and single lever L, whereby the wheels may be adjusted simultaneously, one up and the other down, substantially as and for the purposes herein set forth.

3. The combination of the bail F, plow-beam

N, and the double clamp S, having each side made in two parts, substantially as shown and described, and for the purposes set forth.

In testimony that I claim the foregoing I have hereunto set my hand this 28th day of 15 November, 1879.

G. H. WARREN.
